(57) **CLAIM**

The ornamental design for a forehead support frame component for a patient interface, as shown and described.

DESCRIPTION

FIG. 1 is a perspective view of a forehead support frame component for a patient interface of our design;

FIG. 2 is a front view thereof;

FIG. 3 is a rear view thereof;

FIG. 4 is a top view thereof;

FIG. 5 is a bottom view thereof;

FIG. 6 is a right side view thereof, with the left side view being a mirror image thereof; and,

FIG. 7 is a reverse perspective view thereof.

The broken lines showing environment or structure of the forehead support frame component for a patient interface are for illustrative purposes only and form no part of the claimed design.

The dotted lines in FIGS. 5 and 7 represent the border between claimed and non-claimed subject matter and form no part of the claimed design.
